TOILET BOWL

Harry Hague, Glendale, and Thomas H. Crowther,
Los Angeles, Calif.

Application October 13, 1931, Serial No. 568,546

14 Claims. (Cl. 4—252)

Our invention relates to a toilet bowl and has for its principal objects, the provision of an improved toilet bowl that is relatively simple in construction, inexpensive of manufacture and which is supported entirely from the wall without resting on the floor, further, to provide a toilet bowl having a relatively simple and effective siphon connection which acts when the bowl is flushed, to remove the contents of the bowl with very little if any, noise during the siphonic action and during the refilling of the bowl, further, to provide a bowl having a water sealed connection with the sewer or other outlet and further, to provide a toilet bowl having a minimum number of calked joints, thereby minimizing the time, labor and consequent expense of installation and repairs and at the same time minimizing the possibility of leakage.

Further objects of our invention are, to provide a sanitary toilet bowl having a direct deep water seal so as to effectively prevent sewer gases from rising through the bowl and its connections into the room or building in which the bowl is located and to provide a bowl having the highly desirable hygienic feature of a low seat so that the users of the bowl have the prescribed posture while occupying the seat.

Further objects of our invention are, to generally improve upon and simplify the construction of the existing forms of wall supported toilet bowls, to provide simple and effective means for breaking the siphonic action at the termination of the flushing action, further, to provide the siphon element of the bowl with a readily accessible, normally closed opening, that enables the interior of the siphonic element to be easily reached for the purpose of removing an object of material that tends to clog or close the passage way through the outlet from the bowl and further, to provide the bowl with an overflow which will carry off water that rises above the normal level in the bowl, thereby eliminating all possibility of overflow of the bowl in the event that the siphon element or the outlet from the bowl becomes clogged.

With the foregoing and other objects in view, our invention consists in certain novel features of construction and arrangement of parts that will hereinafter be more fully described and claimed and illustrated in the accompanying drawings, in

50 which:

Fig. 1 is a perspective view of a toilet bowl constructed in accordance with our invention and said bowl being supported by a wall structure.

Fig. 2 is a vertical section taken approximately 55 on the line 2—2 of Fig. 1.

Fig. 3 is a cross section taken on the line 3—3 of Fig. 2.

Fig. 4 is a horizontal section taken on the line 4—4 of Fig. 2.

Fig. 5 is a rear elevational view taken looking 60 in the direction indicated by the arrow 5 in Fig. 2.

Fig. 6 is a top plan view, with parts in section of a modified form of the toilet bowl.

Fig. 7 is a vertical section taken on the line 65 7—7 of Fig. 6.

Fig. 8 is a rear elevational view taken looking 70 in the direction indicated by the arrow 8 in Fig. 6.

Fig. 9 is a side elevational view of the modified form of toilet bowl.

Fig. 10 is an enlarged vertical section taken approximately 75 on the line 10—10 of Fig. 9.

Fig. 11 is a rear elevational view of the modified form of the toilet bowl with the siphon element removed.

Fig. 12 is a vertical section taken on the line 75 12—12 of Fig. 2.

Referring by numerals to the accompanying drawings and particularly to the construction illustrated in Figs. 1 to 5 inclusive, 10 designates a plate of metal that serves as a support for the 80 bowl and said plate is rigidly secured to the wall structure and preferably to a pair of studs S by means of bolts 11. Obviously this plate 10 may be secured to any suitable upright structure other than a wall.

85 A bowl 12, preferably of vitrified earthen material, is provided with a rearwardly projecting body 13 that is substantially rectangular in shape and formed in said rearward extension is a chamber 14, which when the bowl is properly applied to plate 10, is closed on the rear side by said plate 10.

90 Formed in the upper portion of the body 13, is an opening 15, that is normally closed by a hinged plate or cover 16, thereby giving access to the 95 interior of the chamber 14 and the parts that are located therein.

95 Formed through the upper portion of the body 13 is a horizontally disposed opening 17 that communicates with the flushing water duct 18, that 103 extends around the upper portion of bowl 12 on the interior thereof and there being discharge openings 19 formed through the wall below the duct 18, in order to permit the flushing water to flow down the inner surfaces of the bowl.

105 A hinged seat 20 of conventional form and construction is arranged on top of the bowl.

110 Communicating with the rear end of the opening 17, is one end of a flushing water pipe 21 that leads through the upper portion of plate 10

to a suitable source of water supply and located in said pipe within the chamber 14, is a flushing valve 22, of any desired construction and which is controlled by a knob or hand lever 23 that is located on the side of member 13.

Leading from the lower portion of the chamber within bowl 12 rearwardly through the body 13, is an outlet opening 24 and formed in body 13 immediately below said opening is a relatively small chamber 25.

Leading downwardly from the lower portion of opening 17, through the sides of the body 13, are ducts 26 that communicate with the sides of chamber 25.

15 Formed through the wall between chamber 25 and outlet opening 24, are openings 27 that are inclined so that they may direct jets of water upwardly and rearwardly from the lower portion of opening 24 through the rear end thereof.

20 Formed integral with plate 10 and positioned within chamber 14 is a housing 28 within which is formed a spirally disposed siphon chamber 29, the same occupying a plane substantially parallel with plate 10 and therefore at right angles to the major axis of the bowl 12.

The inner lower end of the housing 28 projects a short distance horizontally and said end is provided with a flange that surrounds the corresponding end of the spiral siphon chamber 29 and this flange is secured in any suitable manner, preferably by means of studs and nuts to the rear lower face of the body 13 so that the lower inner end of the siphon chamber 29 communicates directly with the rear end of discharge opening 24 (see Fig. 2). This joint between the siphon housing 28 and body 13 may be packed or caulked in any suitable and wellknown manner to form a watertight joint.

40 The outer end portion of the siphon housing 28 is formed integral with and extends through plate 10, thence downwardly and the lower end of said housing is suitably connected behind plate 10 to a waste or outlet pipe 30 that leads to the sewer or other outlet.

45 Formed in the upper portion of siphon housing 28 is an opening that is normally closed by a normally removable plug 31, thereby permitting ready access to the siphon chamber 29 for the purpose of cleaning the same or removing obstacles therefrom.

55 Leading from the rear portion of the chamber within bowl 12, just above the forward end of outlet opening 24, is a vent duct 32 that leads upwardly and rearwardly through the body 13 and the upper rear end of this duct communicates with a tube 33 and the latter being connected to the top of the siphon housing 28 and communicating with the top of the chamber 29 therein. This vent duct and tube provide means for breaking the siphon within the chamber 29 when the water lever lowers to a predetermined point within bowl 12.

60 Formed in the side wall of the bowl 12, just below the flushing water duct 18, is a series of apertures 34 that communicate with a duct 35, that is formed through the wall of said bowl and through body 13 and the rear end of this duct communicates with a tube 36 that leads rearwardly through chamber 14, thence through plate 10, thence downwardly and the lower end of said tube communicates with the pipe through the lower portion of the housing 28.

75 These apertures 34, duct 35 and pipe 36 function as an overflow to permit the escape of water

from the bowl in the event that an obstruction or clogging should cause the water within said bowl to rise to an abnormal level. Pipe 36 is provided within chamber 14 with a trap 37 to prevent backflow of gas or foul air from the waste pipe 30 to the interior of the bowl.

80 The apertures 34 are located directly beneath a jet opening 38 that is formed in the wall below duct 18 and thus each time the bowl is flushed a certain amount of fresh water will pass through the overflow outlet connection.

85 Under normal conditions the level of the body of water in the lower portion of bowl 12 is above the lower end of duct 32 and this level extends to the top of the partition within the siphon chamber 29.

90 When knob of handle 23 is actuated to open flush valve 22, water will flow from supply pipe 21 through opening 17, thence through duct 18 and thence through outlet openings 19 downwardly into the chamber within bowl 12.

95 A certain amount of water discharging into opening 17 will flow downwardly through ducts 26 into chamber 25 and this water will discharge in jet form upwardly and rearwardly into the lower portion of the siphon chamber 29, thereby tending to accelerate the flow of the body of water from the bowl into the siphon chamber and thereby quickly fill said chamber so as to establish siphonic action.

100 The suction produced by the establishment of siphonic action in chamber 29 will quickly draw water from the bowl 12 through outlet 24, thence through the siphon chamber and said water will discharge downwardly through the waste or outlet pipe 30.

105 As soon as the water level in bowl 12 passes below the lower end of duct 33, the siphon within chamber 29 will be broken, with the result that the suction of the water within bowl 12 will cease and said bowl will refill to its normal level by water that enters the bowl through supply pipe 20 and flush valve 22, which latter automatically closes after a predetermined flushing period.

110 As heretofore stated, all danger of overflowing of the water that discharges into the bowl is eliminated by the provision of the overflow connections 34, 35 and 36 and each time the bowl is flushed a certain amount of fresh water will discharge through the overflow connection from jet 125 opening 38.

115 Plate 10 is rigidly secured to the wall structure and preferably the studs therein by means of bolts and said plate rests directly upon the floor, thereby providing a very strong and substantial support for the bowl so that it is not necessary to support the outer portion of the latter from the floor.

120 Plate 10 may be secured to the wall structures or studs so as to hold the bowl 12 at any desired elevation and in this connection it may be stated that it is the present practice of architects and builders to follow the suggestion of health authorities and physicians to arrange the bowls so that the seats on the tops thereof are considerably lower than the toilet bowls heretofore installed.

125 In the modified form of bowl illustrated in Figs. 6 to 11 inclusive, the construction of the bowl is very similar to the construction heretofore described with the exception that the chamber 14 in the rearwardly extending body of the bowl is eliminated and the spirally formed housing 28^a that contains the siphon chamber, is formed integral with the rear side of a plate 10^a.

and which latter is directly connected by means of bolts 11^a to the body 13^a that projects rearwardly from bowl 12^a.

Plate 10^a which is secured to the wall structure in any suitable manner, extends a short distance above the body 13^a and formed in this upwardly projecting portion is an opening 10^b that is normally closed by a removable plate 10^c, thereby giving access to the interior of the wall structure and the parts that are located therein.

A packing ring or gasket 40 is located between the rear face of the body 13^a and plate 10^a around the outlet opening 24^a in the lower portion of the bowl and around the opening into the siphon chamber 29^a in housing 28^a.

In this modified construction, a flush water supply pipe 21^a provided with a flush valve 22^a, leads to opening 17^a that discharges into flushing duct 18^a and leading from the rear portion of the chamber within the bowl below the normal water level upwardly and rearwardly to the top of the siphon chamber 29^a, is a duct 32^a that admits air to the siphon chamber when the water level in the bowl lowers to a point below the inlet end of said duct.

This form of bowl is also provided with a chamber 25^a in the lower portion of the bowl and leading thereto from inlet opening 17^a, are ducts 26^a.

Inclined jet openings 27^a lead from the rear portion of chamber 25 and are adapted to direct jets of water upwardly and rearwardly into the intake end of the siphon chamber 29^a, the same as the jet openings 27 heretofore described.

Thus it will be seen that we have provided a toilet bowl that is relatively simple in construction, inexpensive of manufacture and very effective in performing the functions for which it is intended.

Installation of the bowl can be effected between 16 inch center studs in a 6 inch wall and connections made to the sewer or outlet pipe without resorting to the usual cutting of studs and floor joists which practice is necessary with bowls of the present construction and materially weakens the building structure.

The chamber 14 in the rear portion of the bowl enables the siphon and other parts of the structure to be easily reached for the purpose of inspection, repairs and replacements and in the event that the outlet 24 or siphon chamber becomes clogged, the cleanout plug 31 may be readily removed to give access to the siphon chamber and permit the ready removal of the obstruction.

The plate 10, with the siphon housing and associated parts may be used in connection with urinals, bathtubs, laundry trays, wash bowls, kitchen sinks and like structures for the purpose of effecting a discharge of the water from the trays, bowls and other containers, in much less time than is required by the generally used gravity and trap methods and at the same time producing a larger and better water seal for protection against sewer gases.

It will be understood that minor changes in the size, form and construction of the various parts of our improved toilet bowl may be made and substituted for those herein shown and described without departing from the spirit of our invention, the scope of which is set forth in the appended claims.

We claim as our invention:

1. In a toilet bowl, a plate adapted to be rigidly secured to a supporting structure, a bowl detachably secured to said plate, said bowl having an outlet and a housing formed integral with said

plate and connected to the outlet from said bowl, which housing is provided with a siphon chamber.

2. A toilet bowl as set forth in claim 1, and with the upper portion of said housing provided with a normally closed cleanout opening.

3. A toilet bowl provided in its rear portion with a chamber, a plate applied to the rear side of said bowl and closing said chamber, a housing secured to said plate and disposed within the chamber in the rear portion of said bowl, said housing having a siphon chamber, one end of which is connected to the outlet from the bowl and the other end of said chamber extending to the exterior of the plate and being connected to a waste pipe.

4. A toilet bowl as set forth in claim 3, with an opening formed in the upper rear portion of the toilet bowl and communicating with the chamber therein and a closure for said opening.

5. The combination with a plate that is adapted to be secured to a supporting structure, of a toilet bowl secured to and projecting from said plate, said toilet bowl having an outlet opening, a housing secured to said plate and provided with a vertically disposed spiral siphon chamber that occupies a plane substantially parallel with said plate and at right angles to the major axis of the bowl and one end of which siphon chamber is connected to the outlet from the bowl.

6. The combination with a toilet bowl having an outlet opening, of a plate to which the rear portion of said bowl is secured and a housing carried by said plate, said housing having a vertically disposed spiral siphon chamber, one end of which is connected to the outlet from the bowl.

7. A toilet bowl as set forth in claim 1, with the communicating openings between the siphon chamber and the outlet from the bowl located below the normal water level within said bowl.

8. A toilet bowl provided with an outlet opening, a housing connected to said bowl, said housing having an inlet opening that communicates with the outlet opening from the bowl and said inlet and outlet opening being located wholly below the normal water level within the bowl.

9. A toilet bowl provided with an outlet opening, a housing connected to said bowl, which housing is provided with a siphon chamber having an inlet opening that communicates with the outlet opening from the bowl and a packed joint between said inlet and outlet openings, which joint is located wholly below the normal water level within the bowl.

10. In a toilet bowl, a plate adapted to be rigidly secured to a supporting structure, a bowl detachably secured to said plate, said bowl having an outlet opening, a siphon chamber carried by said plate and having an inlet opening that communicates with the outlet opening from said bowl and a duct leading upwardly through the rear portion of the bowl through said plate and to the upper portion of the siphon chamber.

11. In a toilet bowl, a plate adapted to be rigidly secured to a supporting structure, a bowl detachably secured to said plate, said bowl having an outlet opening, a siphon chamber carried by said plate and having an inlet opening that communicates with the outlet opening from said bowl, there being a duct formed through the rear portion of the bowl and a duct leading from the upper portion of the siphon chamber to the upper rear portion of said first mentioned duct.

12. A toilet bowl, provided in its rear portion with a chamber, said bowl having an outlet lead-

- ing from its lower portion to the lower portion of said chamber, a siphon chamber arranged within the chamber in the rear portion of said bowl, one end of which siphon chamber is detachably connected to the outlet from the bowl, the other end of said siphon chamber being connected to a waste pipe and a duct leading from a point adjacent to the outlet from the bowl to the upper portion of said siphon chamber. 5
- 10 13. A toilet bowl, comprising a bowl body and a substantially rectangular housing formed integral with the rear portion of said bowl body, said housing having a chamber, said bowl having an outlet leading from its lower portion into the lower portion of the chamber within said housing, a separately formed siphon chamber located in the chamber within said housing, one end of which siphon chamber is detachably connected to the outlet from the bowl at a point below the normal water level within said bowl, the opposite end of said siphon chamber being connected to a waste pipe and a duct leading through the rear portion of the bowl from a point adjacent to the outlet therefrom to the upper portion of said siphon chamber. 15
- 15 20 13. A toilet bowl, comprising a bowl body and a substantially rectangular housing formed integral with the rear portion of said bowl body, said housing having a chamber, said bowl having an outlet leading from its lower portion into the lower portion of the chamber within said housing, a separately formed siphon chamber located in the chamber within said housing, one end of which siphon chamber is detachably connected to the outlet from the bowl at a point below the normal water level within said bowl and the oppo-
- site end of said siphon chamber being connected to a waste pipe. 14. A toilet bowl, comprising a bowl body and a substantially rectangular housing formed integral with the rear portion of said bowl body, said housing having a chamber, said bowl having an outlet leading from its lower portion into the lower portion of the chamber within said housing, a separately formed siphon chamber located in the chamber within said housing, one end of which siphon chamber is detachably connected to the outlet from the bowl at a point below the normal water level within said bowl, the opposite end of said siphon chamber being connected to a waste pipe and a duct leading through the rear portion of the bowl from a point adjacent to the outlet therefrom to the upper portion of said siphon chamber. 80
